DOOR HANGER

Louis F. Dettenborn, Hartford, Conn.

Application October 25, 1932, Serial No. 639,467

5 Claims. (Cl. 20—19)

The present invention relates to vertical doors having a swinging movement into and out of the door opening, and relates especially to doors for wardrobes, closets, lockers, and the like of the type adapted to be used in schools and other buildings. More particularly, the invention relates to the manner in which the door is mounted.

It is an aim of the present invention to provide improved means for supporting a door of this type for swinging movement about an axis passing vertically through the door and also about a parallel axis located adjacent one side edge of the door and at the side of the door opening, said means being so arranged that the door will have a predetermined movement without the use of tracks or the like.

Another aim of the present invention is to provide an improved door mounting which admits of easy operation by the application of a relatively small force thereto.

An object of the present invention is to provide an improved hanger for a door of this character which effects the complete closing and opening of the door when the door has been moved a predetermined extent towards either of these positions. With this object in mind, my improved hanger includes means for automatically and effectively moving the door to its fully open or fully closed position after the door has been partially manually moved to either of these positions.

Another object of the present invention is to provide an improved device of this kind in which the door is free of any obstructions at the lower end of the opening in the wardrobe, either when the door is open or closed. Thus, there are no parts over which children or other users of the device are apt to stumble or trip. Such a structure also simplifies the sweeping out of the wardrobe.

A further object of the present invention is to provide a device of this kind which is simple in construction, comprises few parts, and may be cheaply manufactured, admits of easy installation, and is not apt to get out of order.

Other objects will be in part obvious, and in part pointed out more in detail hereinafter.

The invention accordingly consists in the features of construction, combination of elements and arrangement of parts which will be exemplified in the construction hereinafter set forth and the scope of the application of which will be indicated in the appended claims.

In the accompanying drawings, wherein is shown, for illustrative purposes, one embodiment which the present invention may take,

Fig. 1 is a rear elevation, with parts broken away, of a door and a frame therefor with my improved door hanger applied thereto;

Fig. 2 is a top plan view of the same with parts broken away and parts in section; and

Fig. 3 is an end view of the same with parts broken away and parts in section.

Referring more particularly to the drawings, A generally designates a wardrobe or the like having an opening bounded by a frame upon which is hung a door C by means of my improved door hanger or carrier, generally designated D.

While the wardrobe is here shown as having one opening and one door, it is to be understood that the wardrobe may be of any desired size and may be provided with as many openings and doors as desired.

The door frame, which may be of any suitable construction, has a lintel 5 extending across the top of the opening of the wardrobe A, and side uprights 6 and 7. The doorway may have the usual casing comprising the overhead member 8 and upright side members 9 and 10, the latter of which constitutes a jamb for one edge of the door. Secured to the rear edge of the upright 6 is a jamb strip 11.

Secured at spaced apart points to the inner face of the side member 10 are a plurality of brackets 16. These brackets 16 are provided with a suitable number of openings adapted to receive screws 17 or the like by means of which the brackets are attached to the member 10. The lowermost bracket is provided with two spaced apart shelves or ledges 18 and 19 each of which is disposed at substantially right angles to the main body portion of the bracket, while each of the center and upper brackets has only one such shelf 18. All of these shelves 18 and 19 are provided with aligned openings through which passes a shaft 20. Intermediate the shelves 18 and 19 of the lower bracket 16, the shaft 20 has an arm 21 fixed thereto by means of set screws 22 or the like.

The free end of the arm 21 is provided with an opening which receives a pivot pin 23 carried by a pivot plate 24, mounted upon the lower portion of the door C closer to the side edge thereof which is adjacent to the shaft 20 when the door is in closed position, than the outer edge. The plate 24 may be secured to the door by means of screws 25 or other suitable fastening means. Disposed between the bottom of the arm 21 and the upper face of the shelf 19 of the lowermost bracket 16 and surrounding the shaft 20 is a ball race 26 containing ball bearings 27.

The upper end of the shaft 20 extends upwardly beyond the shelf 18 of the upper bracket 16, and fixed to this upper extended end portion of the shaft 20 is an arm 28. The free end of the arm 28 5 is provided with an opening which receives a pivot pin 29 carried by a pivot plate 30 mounted upon the top portion of the door C, the pivot plate 30 and its pivot pin 29 being in vertical alignment with the pivot plate 24 and its pivot pin 23 respectively. The pivot plate 30 is fixed to the door C by means of screws 31 or the like.

The plate 30 carries an arm 32 which may be formed integral therewith, and extends therefrom inwardly of the door. The free end of this arm 32 15 has pivoted thereto, as at 33, a link 34. The pivot 33 may be in the form of a rivet so as to prevent the separation of the arm 32 and the link 34. The other end of the link 34 is pivotally received by the reduced end of a stud 35, and is held thereon by means of a cotter pin 36 which passes through an opening in the free end of the stud. The stud 35 is fixed to an attaching member 37 which is mounted upon the under surface of the lintel 5 to which it may be secured by means 20 of screws 38 or the like. A coil spring 39 surrounds the stud 35 and has one end thereof secured to the member 37, as by a rivet 40, and the other end secured to the link 34, as by a rivet 41. The spring 39 is so formed and arranged that 25 when the pivotal connection between the arm 32 and link 34 is past dead center, when the parts are moving to either an open or a closed position, it will tend to move the link 34 toward the inner side of the door C and thereby complete the opening or closing operation, as the case may be. It is thus apparent that the door C will be automatically opened or closed without the necessity 30 of applying enough force to completely open or close the same provided enough initial manual force is applied to carry the parts past dead center.

It is also noted that the shaft 20 and the lower arm 21 are carried by the frame above the lower end thereof and, therefore, the arm 21 and shaft 20 will be spaced from the floor upon which the wardrobe stands and that no threshold is employed so that there will not be any parts over 45 which the users of the wardrobe may stumble and so that any dirt or waste material which may accumulate on the floor will not interfere with the proper operation of the door and may be readily swept out of the wardrobe.

In the operation of the device, assuming that the door C is in the closed position, as indicated in full lines in Fig. 2, and it is desired to open 50 the door, force may be applied to the door at any point along the edge thereof adjacent the shaft 20. This will impart to the door swinging movement so that the various parts will be moved to the position indicated in dotted lines at the extreme right-hand end of Fig. 2. During the initial 55 movement of the parts toward open position, the arm 32 forces the link 34 inwardly of the wardrobe against the tension of the spring 39 until the parts have moved sufficiently far to carry the pivotal connection 33 past dead center. The line 60 a—a of Fig. 2 indicates the dead center line. The spring 39 will then become effective to move the link 34 to the dotted line position of Fig. 2 referred to above, thereby moving the door C 65 and other parts to full open position. To close the door, force is applied to the outer edge of the door and, as the parts move toward the full line 70 position of Fig. 2, the arm 32 moves the link 34 inwardly of the wardrobe against the tension of the spring 39 until the connection 33 is moved 75

past dead center in the opposite direction. The spring 39 will then take effect to move the parts into complete closed position shown in full lines in Fig. 2.

It will be noted that the door C, during its opening and closing movements, pivots about the pivot pin 29, as an axis, which is parallel to the pivotal axis of the arms 21 and 28 and that the arm 32 and link 34 guide the door in its pivotal movement about its axis 29 until the parts have passed dead center. The spring 39 then becomes effective to complete the opening or closing movement of the door, as the case may be, in the manner described above.

As many changes could be made in the above construction and many apparently widely different embodiments of this invention could be made without departing from the scope thereof, it is intended that all matter contained in the above description or shown in the accompanying drawings 90 shall be interpreted as illustrative and not in a limiting sense.

It is also to be understood that the language used in the following claims is intended to cover 100 all of the generic and specific features of the invention herein described and all statements of the scope of the invention which, as a matter of language, might be said to fall therebetween.

I claim as my invention:

1. In combination, a wardrobe or the like having 105 a door opening, a shaft journalled in the wardrobe adjacent one side edge of the door opening, an upper arm and an aligned lower arm fixed to said shaft, a door located, when in closed position, between said arms, means for pivotally connecting said door between its side edges to the free ends of said arms about an axis parallel to the axis of said shaft, an arm fixed to and extending rearwardly from said door adjacent the axis about which the door is swung, and a 110 link pivotally connected at one end to the free end of the last mentioned arm, said link being pivotally connected at its other end to said wardrobe adjacent the plane of the door opening.

2. In combination, a wardrobe or the like having 115 a door opening, a carrier pivoted about a vertical axis adjacent one side of the door opening, a door pivotally carried by said carrier for turning movement about an axis parallel to the axis of said carrier, said door being adapted to 120 be moved from the door opening to a position along one side of the wardrobe, and means for completing the opening and closing movements of the door after the door has been moved a predetermined extent towards either of its extreme 125 positions.

3. In combination, a wardrobe or the like having 130 a door opening, a carrier pivoted about a vertical axis adjacent one side of the door opening, a door pivotally carried by said carrier for turning movement about an axis parallel to the axis of said carrier, said door being adapted to be moved from the door opening to a position along one side of the wardrobe, and means for automatically completing the opening and closing movements of 135 the door after the door has been manually moved a predetermined extent towards either of its extreme 140 positions.

4. In combination, a wardrobe or the like having 145 a door opening, a carrier pivoted about a vertical axis adjacent one side of the door opening, a door pivoted between its side edges on the carrier and on an axis parallel to the axis of swinging movement of the carrier, an arm extending from the door between the side edges of the latter, a link 150

5 pivotally connected at one end to the wardrobe and at the other end to said arm, and spring means associated with said link for completing the opening and closing movements of the door after the door has been moved a predetermined extent towards either of its extreme positions.

5. In combination, a wardrobe or the like having a door opening, a carrier pivoted about a vertical axis adjacent one side of the door opening, a door

pivoted between its side edges on the carrier and on an axis parallel to the axis of swinging movement of the carrier, an arm extending from the door between the side edges of the latter, a link pivotally connected at one end to said arm at a point spaced from the plane of said door, and a fixed pivot for pivotally connecting the other end of said link to the wardrobe.
